UNITED STATES PATENT OFFICE.

DANIEL WOODHEAD, OF CHICAGO, ILLINOIS.

DESIGN FOR A LIGHTING-FIXTURE.

48,621.

Specification for Design.

Patented Feb. 22, 1916.

Application filed November 23, 1914. Serial No. 873,649. Term of patent 3½ years.

To all whom it may concern:

Be it known that I, DANIEL WOODHEAD, a citizen of the United States of America, residing at Chicago, in the county of Cook and State of Illinois, have invented a new, original, and ornamental Design for Lighting-Fixtures, of which the following is a specification, reference being had to the accompanying drawings, forming part thereof.

Figure 1 is a view in elevation of a lamp

shade holder embodying my design. Fig. 2 is a top plan view thereof.

I claim:

The ornamental design for a lighting fixture, as shown.

DANIEL WOODHEAD.
